UNITED STATES PATENT OFFICE.

HARRY ABBEY SEDGWICK, OF MADISON, WISCONSIN, ASSIGNOR TO MADISON-KIPP LUBRICATOR COMPANY, A CORPORATION.

LUBRICATOR.

No. 903,897.

Specification of Letters Patent.

Patented Nov. 17, 1908.

Application filed November 23, 1907. Serial No. 403,557.

To all whom it may concern:

Be it known that I, HARRY A. SEDGWICK, a citizen of the United States, residing at Madison, in the county of Dane and State of Wisconsin, have invented certain new and useful Improvements in Lubricators, of which the following is a specification, reference being had therein to the accompanying drawing.

10 This invention relates to a force-feed lubricator and has for its object to simplify the construction thereof and to produce a mechanism, the parts of which are few in number and easily machined and assembled.

15 It has for its especial object the provision of a sight-feed with the smallest possible number of additional parts.

These and other objects of the invention and the advantages thereof will be herein-
20 after fully set forth.

In the accompanying drawings, Figure 1 is a perspective view of a lubricator as a whole. Fig. 2 is a view in vertical cross-section of the lubricator taken through the 25 axis of the piston. Fig. 3 is a view in vertical cross-section taken through the axis of the piston in a plane at right-angles to that of Fig. 2. Figs. 4 and 5 are fragmentary horizontal cross-sections in the plane of the 30 upper pair of ports, showing the piston in two different positions. Fig. 6 is a view of a modified form of piston. Figs. 7 and 8 are vertical and horizontal cross-sectional views, respectively, of a multiple lubricator embodying my invention. Fig. 9 is a fragmentary horizontal cross-section in the plane of the 35 upper pair of ports, showing the modified form of piston of Fig. 6.

The mechanism embodying my invention 40 may be mounted within an oil tank or casing 2, which is generally rectangular in shape and may be an iron casting as here shown. A portion of the top 3 is bolted or otherwise secured to the casing in order that it may be 45 removed to refill the oil reservoir. Mounted in the oiltight bushings 4-4 in the walls of the casing is the shaft 5 which carries the worm 6. Mounted in bearings 7-7 carried by the other two walls of the casing is the 50 shaft 8 at right angles to and some distance above the shaft 5. To this shaft is rigidly secured the worm wheel 9, engaging with the worm 6.

It will be understood that the plunger 55 actuating shaft 8 may be driven by any

other suitable means, as by a ratchet secured to a projecting end of shaft 8 driven by any convenient reciprocating part of the engine. In the worm and wheel drive mechanism shown, the shaft 5 is driven by suitable 60 gearing from some rotating part of the engine. The cam element 10 is rigidly mounted upon the shaft 8 by means of the set-screw 11. It is provided with the eccentric cam surface 12 and the projecting arm 13. 65 The pump plunger or piston 14 is pivotally connected to the member 15 which serves as an eccentric strap and is also provided with a lateral or spiral cam surface 16, which engages with the arm 13. The upper cylindrical end 41 of the member 15 is held in position axially by the bushing 17 seated in the top of the casing. As the shaft 8 rotates, the piston is reciprocated longitudinally by the engagement of the projecting 70 part of the cam 12 alternately with the upper and lower inner faces 18 and 19, respectively, of the member 15. The piston is likewise oscillated through a small angle by the engagement of the arm 13 with the 75 cam surface 16. The piston operates within the cylinder 20 formed by drilling a vertical hole in the casting 21. This casting is provided with the intakes 22 and 23 and the discharge openings 24 and 25. From the 80 discharge opening 24, the duct 26 leads upwardly through the top of the lubricator casing to the sight-feed mechanism 27. The duct 28 leads from the sight-feed mechanism back to the intake 23. The duct 29 leads to 85 the bottom of the oil tank where it has a free opening communicating with the body of oil in the reservoir. Piping leads from the discharge opening 25 to the engine parts desired to be lubricated. 95

The cylinder 20 has two chambers 30 and 31 of different bore, the diameter of the upper chamber being the larger. The ports of the upper cylinder 32 and 33 communicate with the intake and discharge openings 100 22 and 24, respectively. The ports 34 and 35 communicate with the intake and discharge openings 23 and 25, respectively. The piston is of one diameter in its upper portion and of another and smaller diameter in its lower 105 portion. These two parts of the piston correspond with the two diameters of the cylinder and fit snugly therein. Each part of the piston is provided with grooves 36 and 37, commencing at the lower end of its 110

working face and extending upwardly short of the other end thereof by a distance at least equal to the maximum stroke of the piston. The grooves 36 register with the 5 ports 32 and 34 at one point in the cycle of movements of the plunger, and thereafter the grooves 37 register with the ports 33 and 35 at a time when the grooves 36 are out of registry with their corresponding 10 ports.

The mechanism, as a whole, is so constructed and the cam surface so designed that while the intake ports and their corresponding grooves are in registry, the piston 15 is raised vertically to its upper limit. During this operation the oil flows from the reservoir and the sight-feed chamber into the space inclosed between the shoulder 38 of the piston and the shoulder 39 of the 20 cylinder, on the one hand, and into the space between the lower ends of the plunger and cylinder, on the other. The plunger is then rotated until the discharge ports and their corresponding grooves are in registry, where- 25 upon it is moved downwardly discharging the oil present in the lower portion of each of the two parts of the cylinder. One portion of oil will be sent to the sight-feed device and the other portion will be pumped 30 to the parts of the engine to be lubricated.

In Figs. 6 and 9, I have shown a piston provided with but one groove. When this construction is used the oscillation must obviously be designed to extend over the angle 35 between the intake and discharge ports.

I have provided a means for varying the length of the stroke of the plunger. The cylindrical extension 41 of the member 15 has threaded engagement with the sleeve 40. 40 The piece 42, consisting of two pins 45 and 46, and the connecting yoke 47, is free to move vertically in the sockets 48 and 49 formed in the member 15. The under side of the yoke 47 engages with the eccentric cam 45 to give the piston the reciprocatory motion described above. The limit of downward movement of this piece can be fixed in any suitable manner as by the enlargement 50 on the upper end of the pin 45. By adjusting 50 the position of the sleeve 40 upon part 41, the upper limit of movement of the piece 42 is correspondingly varied and the distance between the upper and lower strap faces 18 and 19 is increased or decreased. In this 55 manner the lost motion in the engagement of the cam 12 with the faces of the strap 18 and 19 is controlled in amount and the stroke of the plunger varied accordingly. By means of the cap nut 43 and the screw 44, the 60 sleeve 40 is locked in any desired position of adjustment.

In Fig. 6, I have shown the cam yoke member 15 made integral with the piston. The upper bearing should then be held rig- 65 idly in accurate alinement with the cylinder,

to prevent the creation of stresses in the cylinder staff. To obviate the necessity for such accurate machining and rigid connection of the bearing and cylinder, the pivotal connection 51, Figs. 2 and 3, is employed. 70

It will be understood that the feature of a double tandem piston and cylinder can be used, where the piston is of the rotary type, as well as of the oscillatory. Or it can be used where the piston neither oscillates or 75 rotates but has only a motion of reciprocation. The single groove can be used on a piston designed to rotate as well as on one designed to oscillate. Attention is likewise called to the fact that the arrangement of 80 engaging cam members on the drive-shaft and piston extension can be varied without departing from the spirit of my invention.

As shown the two diameters of cylinder and piston are so proportioned that the displacement of the one part of the piston pumping to the sight-feed device is less than the displacement of the lower part, pumping to the engine bearings. That is, the difference in the area of the two circles is less than 90 the area of the smaller circle. This is readily observed to be necessary to avoid completely filling the ducts 26 and 28 and the sight-feed mechanism with oil under high pressure as would otherwise be the case. It is de- 95

sirable to use these lubricator pumps in batteries of three four or more, each pump supplying oil to separate parts of the engine mechanism. A series of cams 10 on the shaft 8 and yokes 15, attached to the piston 100 may be used to drive the several pump mechanisms. But to economize room, enable the use of one small casting for all of the cylinders, and avoid duplication of the cam structures, I have devised the following multiple 105 arrangement and construction, illustrated in Figs. 7 and 8.

52 is the single casting which is drilled to provide a series of six cylinders, and ducts properly connecting the cylinders with the reservoir, the sight-feeds and the engine bearings. I have shown six such cylinders with corresponding pistons. The two outside pistons, 14^a and 14^b are provided with cam yokes, 15^a and 15^b. The channel-shaped cross head 53 engages the shoulders 54 of the outside pistons being slotted at each end for that purpose. The intermediate pistons terminate just under the cross head. In the depending flange 56 of this cross head is drilled a series of holes 56', one for each piston. A corresponding series of slots 57' are cut in the other flange 57 of the cross-head. Pins 58, are screwed into tapped holes 59 in the pistons, the projecting ends 125 engaging respectively the holes and slots.

When the outside pistons are given reciprocatory and oscillatory motions, the engagement of the cross-head with the pins 58 is evidently such as to duplicate these motions 130

in each of the intermediate pistons, the holes 56 being beveled on both outer and inner flange face, in a horizontal direction to permit an oscillatory motion of the pins 58. At the same time any unit in the battery may be disconnected by simply removing its pin 58.

The pins serve to transmit motion of oscillation and also the upward motion of reciprocation. But the downward or pressure stroke is effected by engagement of shoulders 54 with the cross-head and of the cross-head with the upper ends of the intermediate pistons. By this arrangement I gain simplicity 15 and strength of parts.

What I claim is:

1. In a pump, a cylinder, a piston working therein free to reciprocate longitudinally and to oscillate about its axis, and provided with a rigid extension, a drive-shaft directly engaging said extension, the engaging surfaces of said extension and shaft being adapted to both reciprocate and oscillate said piston, substantially as set 25 forth.

2. In a pump, a cylinder, a piston working therein free to reciprocate longitudinally and to oscillate about its axis, and provided with an extension, a drive-shaft 30 directly engaging said extension, the engaging surfaces of said extension and shaft being adapted to both reciprocate and oscillate said piston, the extension being maintained at all times immovable with respect 35 to said piston, substantially as set forth.

3. In a pump, a cylinder, a piston working therein free to reciprocate longitudinally and to oscillate about its axis, and provided with an extension, means for maintaining 40 said extension in axial alinement with said piston, a drive-shaft directly engaging said extension, the engaging surfaces of said shaft and extension being adapted to both reciprocate and oscillate said piston, substantially as set forth.

4. In a pump, a cylinder, a piston working therein free to reciprocate longitudinally and to oscillate about its axis, and provided with an extension, a bearing for said extension 50 in axial alinement with said piston, a drive-shaft directly engaging said extension the engaging surfaces of said shaft and said extension being adapted to both reciprocate and oscillate said piston, substantially as set forth.

5. In a pump, a cylinder, a piston working therein free to reciprocate longitudinally and to oscillate about its axis, and provided with an extension, means for holding 60 said extension in axial alinement with said piston, a drive-shaft directly engaging said extension, said drive-shaft and piston extension having two sets of engaging surfaces, one set being adapted to reciprocate said 65 piston, and the other independent set to

oscillate said piston, substantially as set forth.

6. In a pump, a cylinder, a piston working therein free to reciprocate longitudinally and to oscillate about its axis, and provided with an extension, means for holding 70 said extension in axial alinement with said piston, a drive-shaft directly engaging said extension, said drive-shaft and piston extension having two sets of engaging surfaces, one set for reciprocating said piston, and the other set for imparting an oscillatory motion to said piston independent of said reciprocatory motion, substantially as set forth.

7. In a pump, a cylinder, a piston working therein free to reciprocate longitudinally and to oscillate about its axis, and provided with an extension, a drive-shaft 75 directly engaging said extension, said drive-shaft and piston extension having two sets of engaging surfaces, one for reciprocating said piston, and the other for imparting an oscillatory motion to said piston independent of said reciprocatory motion, substantially as set forth.

8. In a pump, a cylinder, a piston working therein free to reciprocate longitudinally and to oscillate about its axis, and provided with an extension, a drive-shaft directly engaging 85 said extension, the engaging surfaces on said shaft and piston being adapted to give to said piston a motion of longitudinal reciprocation and a motion of oscillation about its axis independent of said motion of reciprocation, substantially as set forth.

9. In a pump, a cylinder, a piston working therein free to reciprocate longitudinally and to oscillate about its axis, and provided with an extension, a drive-shaft 95 directly engaging said extension, the engaging surfaces of said shaft and said extension being adapted to give to the piston a longitudinal reciprocation with a rest or dwell between two successive movements, and an oscillatory motion about its axis to said piston with a rest or dwell between two successive movements of said oscillation, the time of each reciprocating motion coinciding with that of an oscillatory rest and vice versa, substantially as set forth.

10. In a pump, a cylinder, a piston working therein free to reciprocate longitudinally and to oscillate about its axis, and provided with an extension, a drive-shaft 105 directly engaging said extension, said drive-shaft and piston extension having two sets of engaging surfaces, the one being adapted to reciprocate said piston, and the other being adapted to impart an oscillatory motion to said piston independent of said reciprocatory motion, substantially as set forth.

11. In a pump, a cylinder, a piston working therein free to reciprocate longitudinally, 110

an extension for said piston, a drive shaft directly engaging said extension, said piston extension and said shaft having cam faces for imparting a reciprocatory motion to said 5 piston, means for adjusting said engaging faces for varying the length of stroke of the piston, and means self contained in said extension and movable therewith for locking said adjusting means in any position of adjustment, substantially as set forth.

12. In a pump, a cylinder, a piston working therein free to reciprocate longitudinally, provided with an extension, a drive-shaft provided with an eccentric cam adapted to 15 engage opposite faces upon the extension element substantially perpendicularly to the axis of the piston to impart a motion of longitudinal reciprocation to the piston, means for adjusting said opposite faces toward and from each other, and means self-contained in said extension and movable therewith for locking said means in any position of adjustment, substantially as set forth.

13. In a pump, a cylinder, a piston working therein free to reciprocate longitudinally and to oscillate about its axis, provided with an extension element, a drive-shaft element, a lateral faced cam secured to one of the 30 last-named two elements, an engaging member secured to the other element adapted to follow the face of said cam, whereby an oscillatory motion is given to the piston, an eccentric cam on said drive-shaft, said piston 35 extension having opposite faces substantially perpendicular to the axis of the piston, adapted to engage with said eccentric cam, whereby a longitudinal reciprocatory motion is given to said piston, substantially as set forth.

14. In a pump, a cylinder, a piston working therein free to reciprocate longitudinally and to oscillate about its axis, provided with an extension element, a drift-shaft element, 45 a lateral faced cam secured to one of the last-named two elements, an engaging member secured to the other element adapted to follow the face of said cam, whereby an oscillatory motion is given to the piston, an eccentric cam on said drive-shaft, said piston 50 extension having opposite faces adjustable toward and from each other and substantially perpendicular to the axis of the piston, adapted to engage with said eccentric cam,

whereby a longitudinal reciprocatory motion 55 is given to said piston, substantially as set forth.

15. In a pump, a cylinder, a piston working therein free to reciprocate longitudinally and to oscillate about its axis, provided with 60 an extension, a drive-shaft, an eccentric cam secured to said shaft, a yoke-like structure on said extension, having interior faces substantially perpendicular to the axis of the piston to engage said eccentric cam, one of 65 the lateral faces of the yoke being cam-shaped, an arm on said drive shaft adapted to engage said lateral yoke faces, whereby an oscillatory motion is given the piston, substantially as set forth.

70 16. In a lubricator, a series of cylinders, a series of pistons working therein, means for oscillating and reciprocating one of said pistons, and means independent of the aforesaid means for transmitting said motion of 75 reciprocation and oscillation to the remaining pistons, substantially as set forth.

17. In a lubricator, a series of cylinders, a series of pistons working therein, means for oscillating and reciprocating one of said pistons, a cross-head connecting all of said pistons, whereby the reciprocation and oscillation of one may be transmitted to the others, and means for maintaining said cross-head perpendicular to said pistons, substantially 85 as set forth.

18. In a lubricator, a series of cylinders, a series of pistons working therein, each free to reciprocate longitudinally and oscillate about its axis, means for reciprocating and oscillating one of said pistons, a cross-head engaging all of said pistons, means for maintaining said cross-head perpendicular to the axes of said pistons, means for reciprocating and oscillating one of said pistons, means for 95 converting the motion of oscillation and reciprocation in the one of said pistons to corresponding motions of the cross-head, and readily disengageable means for converting the motions of the cross-head into 100 oscillatory and reciprocatory motions in each of the remaining pistons.

In testimony whereof I affix my signature, in presence of two witnesses.
